US00D751578S

(12) **United States Design Patent**
Seo et al.

(10) **Patent No.:** US D751,578 S
(45) **Date of Patent:** ** Mar. 15, 2016

(54) **DISPLAY SCREEN OR PORTION THEREOF
WITH GRAPHICAL USER INTERFACE**

(71) Applicant: **Samsung Electronics Co., Ltd.,**
Suwon-si, Gyeonggi-do (KR)

(72) Inventors: **Jang-Won Seo**, Seoul (KR); **Sun-Young Kim**, Gyeongju-Si (KR)

(73) Assignee: **SAMSUNG ELECTRONICS CO., LTD. (KR)**

(**) Term: **14 Years**

(21) Appl. No.: **29/489,290**

(22) Filed: **Apr. 29, 2014**

(30) **Foreign Application Priority Data**

Dec. 30, 2013 (KR) 30-2013-0066245

(51) **LOC (10) Cl.** **14-04**

(52) **U.S. Cl.**

USPC **D14/485**

(57) **CLAIM**

The ornamental design for a display screen or portion thereof with graphical user interface, as shown and described.

DESCRIPTION

FIG. 1 is a front view of a display screen or portion thereof with graphical user interface, showing our new design; and, FIG. 2 is a front view thereof, as shown in a display screen environment.

The broken lines are for environmental purposes only and form no part of the claimed design.
